UNITED STATES PATENT OFFICE

2,582,003

PIVOTED LAVATORY APPARATUS FOR
RAILWAY CARS

James E. Candlin, Jr., Chicago, Ill., assignor to
Pullman-Standard Car Manufacturing Company, Chicago, Ill., a corporation of Delaware

Original application August 2, 1945, Serial No.
608,502. Divided and this application September
10, 1945, Serial No. 615,478

7 Claims. (Cl. 4—169)

1
The present invention relates to a novel wash-basin unit that is particularly well suited for use in a railway passenger car, or the like, where space is limited. The basin unit is ample in size to serve satisfactorily in a wash room for men or women of the type commonly provided at an end of a standard railway sleeping car, but during those periods of the day when the wash rooms are not in great demand the basin unit may be folded to an inoperative position so as to provide additional free floor space to increase the seating capacity of the car. This is particularly advantageous where the basin unit is used in coaches where more seating capacity is needed for daytime travel than during the nighttime.

The basin unit is compact and substantially self-contained in its entirety with the piping disposed out of the way and at least mostly enclosed. The basin, when in its inoperative position utilizes a minimum of space. The invention provides complete facilities for both fresh and soiled towels and for used razor blades. When the unit is in its inoperative position these facilities are enclosed and disposed out of the way.

The foregoing constitutes some of the principal objects and advantages of the invention, others of which will become apparent from the following description and the drawings, in which:

Fig. 1 is a more or less diagrammatic plan view of the basin forming the subject matter of the present invention;

Fig. 2 is a vertical transverse sectional view shown partially in elevation and taken through the basin unit on line 2—2 of Fig. 1;

Fig. 3 is a sectional view taken on the line 3—3 of Fig. 2;

Fig. 4 is a front elevational view of the basin unit shown in Fig. 2 and showing seats disposed beneath the basin;

Fig. 5 is a more or less diagrammatic view showing the basin unit in operative position with seats disposed therebeneath and illustrated in inoperative position; and

Fig. 6 is a view corresponding to Fig. 5 but showing the basin unit in inoperative position with the adjoining seats in condition for use.

This is a division of the copending application of James E. Candlin, Jr., Serial No. 608,502, filed August 2, 1945.

For illustrative purposes, a specific embodiment of the present invention has been selected, but it is recognized that modifications will appear to those skilled in the art, and it is intended that these modifications may be made without

2
departing from the intended scope of the invention.

Referring now to Fig. 1, the basin unit forming the subject matter of the present invention is illustrated at 62 and comprises an elongated housing 70 provided with three washbasins 71, 72, and 73 spaced lengthwise in the housing 70 and disposed adjacent to the housing front wall 74. This housing 70 has a back wall 75, a bottom wall 76, a top wall 77, and end walls 78 and 79, all of which walls cooperate to form a rectangular box-like enclosure. In the region of each basin, the top wall 77 extends from the back wall 75 only part way forward toward the front wall 74, leaving an opening for each of the basins 71, 72, and 73. Each of the basins 71, 72, and 73 is provided with a flange 80 along its forward edge that projects forwardly and downwardly at 85 to form part of the front wall 74. The bottom wall 76 of the housing 70 overlaps this projecting portion at 81. A flange 86 on the free edge of the basin projections 85 serves as means for fastening these walls together. Along the back of the basin 72 is a horizontal projection 82 provided at its free end with an upstanding flange 83. An angle member 84 serves to fasten the upstanding flange 83 to the top wall 77 of the housing 70.

As best shown in Fig. 2, a cover member, generally indicated at 87, is hinged at 88 to the top wall 77 of housing 70 and extends over the basins 71, 72, and 73. This cover member 87 is provided with a downwardly extending box-like container 89 at its outer end that projects downwardly along the front wall 74 of the box-like housing 70. This container includes for each basin a towel container 89a and a used razor blade container 89b (see Fig. 1). The cover member 87, hinged as it is at 88, may be rotated to an open position indicated in broken lines at 87a in Fig. 2, in which position the washbasins 71, 72, and 73 are made accessible. The box-like container 89 is hollow and, as indicated, for example, in Fig. 4, is provided with a plurality of slots 90, one of which is disposed adjacent to each of the washbasins 71, 72, and 73. These slots 90 provide access into the interior of the member 89a so that fresh towels and the like may be housed inside of member 89 and can be obtained through opening 90. Member 89 may further be provided with smaller slots 91 through which used razor blades may be deposited and held inside the housing member 89b. A lid 92, hinged at 93, may be provided on the member 89 so that the used razor blade container may be

emptied. Electric outlets 155 may be located on the aisle partition 33 as shown in Fig. 4.

Referring to Fig. 1, the housing 70 is mounted between spaced, box-like side members 94 and 95, and is hingedly mounted on these members in a manner shown in Figs. 2 and 3. The hinging arrangement on both sides of the housing 70 comprises a pair of cooperating hinge members 96 and 97, one of which is mounted on the housing 70 and the other on the adjacent end member 94 or 95. As shown in Figs. 2 and 3, the hinge member 96 is provided with a pair of arcuate tracks or slots 98 and 99 adapted to receive cooperating lugs 100 and 101, respectively, projecting outwardly from and forming part of the hinge member 97. Lug 100 is adapted to ride in slot 98, whereas lug 101 rides in slot 99. The curvature of slot 98 is about the lower end of slot 99 as its center, whereas the curvature of slot 99 is about the right-hand end of slot 98, as shown in Fig. 2.

Thus, when the basin unit 62 is in its horizontal position, shown, for example, in room 32b, and also shown in solid lines in Fig. 2, lug 100 is disposed at the left-hand end of slot 98, whereas lug 101 is disposed in the lower right-hand end of slot 99. As the basin 62 is swung downwardly in a clockwise direction, during the first part of its movement the lug 100 moves from the position shown in Fig. 2 to the right-hand end of slot 98, revolving about lug 101 disposed at the lower right-hand extremity of slot 99, during which movement the basin 62 moves somewhat away from aisle wall 33. At the end of this first portion of its clockwise movement toward its inoperative position, the basin unit 62 will assume a position somewhere between its solid line position shown in Fig. 2 and its broken line position shown at 62a, and then the lug 100 will be disposed at the right-hand extremity of slot 98. On continued clockwise rotation of the basin unit 62, lug 101 moves upwardly in slot 99, rotating about lug 100, now disposed at the right-hand extremity of slot 98, until lug 101 reaches the upper left-hand extremity of slot 99. At the end of this movement of lug 101, the basin unit 62 assumes the vertical, inoperative position shown at 62a in Fig. 2 against a pair of cushions 102 that are fixed at spaced points on wall 33. A locking latch 103 may be mounted at each end of the housing unit 70 for holding the basin unit in its lowered, inoperative position, and a second latch 104 may be provided at each end of the housing 70 to support the basin unit 62 in its raised operative position. The details of these latches 103 and 104 form no part of the present invention, as any conventional type latch of sufficient strength will serve satisfactorily.

Referring to Figs. 1 and 2, each washbasin 71, 72, or 73 is provided with a drain pipe, generally indicated at 109, that extends to a common drain header 110. This drain header 110 is disposed closely adjacent to wall 33, and is disposed throughout the length of the basin unit 62. This header 110 is supported in some suitable manner on end member 94 (see Fig. 1), and at the opposite end of the basin unit 62 the header 110 projects into the end member 95 and connects with a vertical riser 111 through a conventional trap 112.

The drain pipe 109 is connected to a basin drain member 108 projecting from the bottom of each of the washbasins 71, 72, and 73, and comprises a segment 113 connected by means of a

ball joint 114 to the basin drain 112 and telescoping at its other end into an intermediate segment 115. A suitable packing gland 116 is provided to seal the telescoping joint. Intermediate segment 115 is connected by means of an elbow 117 (see Fig. 1) and a ball joint 118 to a longitudinally extending member 119, the latter in turn being directly connected to the header 110 through a second elbow 120 and connecting segment 121.

Each of the washbasins 71, 72, and 73 is provided with a cold and hot water faucet 122 and 123, respectively, which discharge into a common outlet 124 into its corresponding washbasin. Cold and hot water pipes 125 and 126, respectively, extend substantially throughout the length of the basin unit 62. The cold water pipe 125 is connected to the cold water faucet 122 through suitable piping indicated generally at 127, while the hot water pipe 126 is connected to the hot water faucet 123 by means of suitable piping 128. These cold and hot water pipes, with their connections to the faucets, are completely housed in housing member 70, as best shown in Fig. 2, and pass through the end wall 78 of the housing into the end member 94 by means of cut-out portions 129 provided both in the end wall 78 and in the adjacent wall of end member 94. The cold and hot water pipes 125 and 126, when they pass into the end member 94, are connected to suitable cold and hot water supply lines, indicated at 130 and 131, respectively, in Fig. 1, by means of flexible connections 132 and 133, respectively. Conventional valves 134 and 135 are disposed, respectively, in the hot and cold water supply lines.

Thus, as the basin unit 62 is rotated from its operative position, shown in solid lines in Fig. 2, to its inoperative position shown in broken lines, each drain pipe 109 enters an opening 136 in the bottom wall 76 of housing 70. The piping is allowed to pivot where necessary by virtue of the various ball joints, such as shown at 114 and at 118, and the changes in length of each of the drain pipes 109 caused by the different pivot points for the basin unit 62 and the pipes are provided by the telescoping joint. The flexible connections 132 and 133 in the end member 94 allow for the movement of the cold and hot water pipes 125 and 126, respectively.

It can thus be seen that the basin unit 62 is of sufficient size and may be suitably arranged in a men's or women's washroom to serve satisfactorily the needs of the passengers normally using these facilities. The greatest demand for washbasins occurs at night before passengers retire and in the morning when they arise. During the remainder of the daytime, there is less need for facilities of this sort, and in the case of day coaches in particular there is a greater need during the daytime for increased seating capacity. A basin unit of the type disclosed herein is particularly well suited for this type of use because of the fact that it may be moved to an out of the way place to clear additional floor space for additional seats.

Provisions for storing fresh and used towels as well as used razor blades form part of the unit, and during those periods of the daytime when the unit is not in use these accessories likewise are so disposed as not to utilize an appreciable amount of space that can be utilized for seats.

I claim:

1. A basin unit comprising an elongated hous-

ing, a plurality of basins in the housing, a movable cover adapted to close the basins and provided with a box-like container, means mounting the cover on the housing for movement between closed position where the basins are covered to open position where the basins are uncovered, the box-like container having an opening therein accessible when the cover is in its open position, a support for the housing, and means pivotally mounting the housing on the support so that the housing may be pivoted from a horizontal to a vertical position.

2. A basin unit comprising an elongated housing, a plurality of basins in the housing, a faucet mounted on the housing adjacent to each basin, water supply means enclosed in the housing and connected to each faucet, a movable cover adapted to close the basins, means mounting the cover on the housing for movement between closed position where the basins are covered to open position where the basins are uncovered, a support for the housing, and means pivotally mounting the housing on the support so that the housing may be pivoted from a horizontal to a vertical position.

3. A horizontal basin unit including a box housing comprising top, bottom, side and front walls, a basin positioned in the top wall, a cover hinged to the top wall and extending over the basin and terminating at the front wall, and a receptacle disposed on the forward edge of the cover and projecting beyond the front wall of the box housing and downwardly along the forward face of the front wall, the receptacle having an opening in its side disposed most adjacent to the front wall of the box housing.

4. A horizontal basin unit including a box housing comprising top, bottom, side and front walls, mounting means for the basin including a substantially pivot-like connection providing for movement of the box housing from horizontal to vertical positions, a basin positioned in the top wall, a cover hinged to the top wall and extending over the basin and terminating at the front wall, and a receptacle disposed on the forward edge of the cover and projecting beyond the front wall of the box housing.

5. A horizontal basin unit including a box housing comprising top, bottom, side and front walls, mounting means for the basin including a substantially pivot-like connection providing for movement of the box housing from horizontal to vertical positions, a basin positioned in the top wall, a cover hinged to the top wall and extending over the basin and terminating at the front wall, and a receptacle disposed on the forward edge of the cover and projecting beyond

the front wall of the box housing and downwardly along the forward face of the front wall, the receptacle having an opening in its side disposed most adjacent to the front wall of the box housing.

6. A horizontal basin unit including a box housing comprising top, bottom, side and front walls, mounting means for the basin including a substantially pivot-like connection providing for movement of the box housing from horizontal to vertical positions, a basin positioned in the top wall, a cover hinged to the top wall and extending over the basin and terminating at the front wall, and a receptacle disposed on the forward edge of the cover and projecting beyond the front wall of the box housing and downwardly along the forward face of the front wall, the receptacle having an opening in its side disposed most adjacent to the front wall of the box housing, and cold and hot water supply faucets mounted on the box housing adjacent to the basin.

7. A horizontal basin unit including a box housing comprising a top, bottom, side and front walls, mounting means for the basin including a substantially pivot-like connection providing for movement of the box housing from horizontal to vertical positions, a basin positioned in the top wall, a cover hinged to the top wall and extending over the basin and terminating at the front wall, and a receptacle disposed on the forward edge of the cover and projecting beyond the front wall of the box housing and downwardly along the forward face of the front wall, the receptacle having an opening in its side disposed most adjacent to the front wall of the box housing, and cold and hot water supply faucets mounted on the box housing adjacent to the basin, and supply piping enclosed in the box housing and connected to the faucets.

JAMES E. CANDLIN, JR.
